(57) **CLAIM**

The ornamental design for a middle handle portion for a floor cleaner, as shown and described.

DESCRIPTION

FIG. 1 is a perspective view of the middle handle portion for a floor cleaner showing our design;

FIG. 2 is a front elevational view thereof;

FIG. 3 is a right side view thereof;

FIG. 4 is a rear elevational view thereof;

FIG. 5 is a left side view thereof; and,

FIG. 6 is a top view thereof.

The portion of the vacuum cleaner shown in broken lines in all views is for illustrative purposes only and forms no part of the claimed design.
